UNITED STATES PATENT OFFICE.

WILLIS C. MILES, OF JERSEY CITY, NEW JERSEY.

COMBINED LAP-BOARD AND BLACKBOARD ATTACHMENT FOR A TABLE-DESK.

1,100,983.

Specification of Letters Patent. Patented June 23, 1914.

Application filed March 7, 1911. Serial No. 612,852.

To all whom it may concern:

Be it known that I, WILLIS C. MILES, a citizen of the United States, residing at Jersey City, in the county of Hudson and State 5 of New Jersey, have invented certain new and useful Improvements in a Combined Lap-Board and Blackboard Attachment for a Table-Desk; and I do hereby declare the following to be a full, clear, and exact description of the invention, reference being 10 had to the accompanying drawings.

In the accompanying drawings, Figure 1 illustrates the improved lap-board and black-board hinged at one end of the table frame, to turn on a transverse axis, the free end being in a position to be held on the lap of the user; the dotted lines represent the 15 position of the black-board when in use and held in place by the desk attached to the under side of a movable table top. Fig. 2 is a sectional view of the table desk illustrated in Fig. 1, but in a closed position, the table top resting upon, and the desk resting 20 within the table frame. Fig. 3 illustrates the black-board or lap-board hinged transversely to the table frame as shown in Fig. 1, the desk employed being constructed or built in the frame, with a hinged top as a writing surface. Fig. 4 is a table desk with the lap- 25 board or black-board attached thereto, and built on lines similar to the one illustrated in Fig. 3, the table top as well as the desk top being made in two sections.

The object of the present invention is to 30 provide a device adapted to enter in combination with a child's table or table desk, arranged to answer a two-fold purpose, viz:—that of a black-board in an upright position, and also that of a lap-board held 35 on the lap of the user in a horizontal position or nearly so to serve the purpose of a slate. To construct an article of this character, applicant employs an ordinary table or stand (child's size) to which a movable top 40 as well as a desk may be connected. Also a tray or receptacle to hold ink, pens, pencils, chalk, etc., may be attached if preferred. To the side or end of the table employed 45 in the said combination, applicant hinges transversely a two-faced black-board arranged to answer the purposes aforesaid.

Heretofore the various forms of table desk have been constructed solely for an adult. Applicant by attaching a black-board and lap-board forms a combination 50 article for the exclusive use of a child which

affords means also whereby two children can use the same. The lap-board answering the use of a slate may also be employed for holding books, papers, pads, etc., when resting 60 on the lap of the user. To this combination a book-case may possibly be attached or it may be omitted when expedient to reduce weight and bulk of the structure.

There are many known ways and means 65 of placing a desk in combination with a table; consequently applicant does not confine himself to any one form of table or desk so long as the same be adapted to receive the invention in combination. Possibly the 70 form of table and desk shown in Fig. 1 of the drawings may be preferred, as the desk answers a two-fold purpose in that it may be employed not only as a desk but also provides means most suitable for holding the 75 black-board upright at a proper angle for use.

Similar letters and numerals refer to similar parts throughout the several views illustrated in the drawings.

Numeral 1 represents an ordinary table 80 suitable for a child.

2 is a movable table top connected to the table as may be preferred and in the form shown or otherwise.

3 is the table frame at one end or side of 85 which applicant attaches his improved black-board and lap-board as set forth.

4 represents a tray or receptacle for ink, pens, pencils, chalk, erasers, etc., or other articles necessary or convenient to the user 90 of the black-board or desk. The same may be located preferably in such a position that the person at the desk as well as the user of the blackboard may have easy access thereto.

5 represents any desk in combination with an ordinary table which will form what is known as a table desk, and the same may be constructed as shown in the drawings or otherwise as may be preferred.

6 are the pigeonholes or compartments comprised in the various desks.

7 represents a desk leaf or closure, and the same may be in the form shown in Fig. 1 or connected as shown in Figs. 3 and 4 or otherwise as may be preferred.

8 is a book-case sometimes connected to the table frame.

9 are the supports to the table and the same may be in the form shown or in any 110 other preferred form suitable to the structure employed.

a represents an improved two-faced black-board arranged to be also employed as a lap-board constructed of pulp and surfaced with a silicate or black-board composition adapted to be written upon with chalk or soap-stone pencil. The said board is so connected that by being manipulated either side may be used as a black-board, the one side while the user is standing, the other side while the user is seated. It will be seen that while the same is held upon the lap of the user, the invention practically serves the purposes of an ordinary slate.

b is the surface or side of the board when the same is employed in the capacity of a slate as aforesaid. *c* represents the other side of the board which, when thrown in an upright position, is adapted for use as a black-board.

d is the end of the board connected or hinged transversely to the end of the table frame, while *e* is the free end of the board.

f represents a prop or any other means employed to hold the black-board in an upright position for use.

Fig. 1 of the drawings illustrates a form of desk connected to the under side of a hinged table top which, when manipulated, is raised and lowered into and out of the frame. Applicant prefers this form of desk as means most suitable to hold the black-board in an upright position as shown by dotted lines. Applicant, however, does not confine himself to either of the forms shown in Figs. 1 and 3 as there are various devices known and in use that may be employed.

It will be noted that in the construction of a device of this character adapted to the use of a child it is not essential that any set rules of construction either in the table, desk or receptacle be followed. Generally the cheapest construction would find the best market as the device is not necessarily an article of furniture like that for the use of an adult. Therefore, a form of stand in lieu of a table with the equivalent of a desk connected thereto might recommend itself to the public which, at the same time, would serve to lighten the structure to such an extent that a child could easily move it from place to place or carry it around. Consequently, applicant does not confine himself to the de-

tails of construction shown since they may vary and the essentials of the invention still be employed.

It will be noted that in all of the forms illustrated, when the desk is closed and not in use, the blackboard member *a* depends loosely, covering the open side of the book case *g*, thereby serving to protect the books therein in the same manner as a door.

Having described my invention, I claim:

1. The combination with a table or stand provided with a movable top, of a normally depending blackboard member provided with an opaque coating on both sides, said blackboard member being pivoted at its upper end to one end of said table or stand below said top to permit the free end of the black-board to be placed on the lap of the user with one opaque face exposed, and a prop member for supporting said black-board member with its free end elevated and the other opaque surface exposed when said top has been moved to open position, said prop member being contained within the table or stand beneath said top when the latter is closed.

2. The combination with a table or stand provided with a book case section located at one end thereof, said table or stand being provided with a movable top, of a door or closure for the book case section comprising a normally depending blackboard member provided with an opaque coating on both sides, said blackboard member being pivoted at its upper end to the end of the table or stand adjacent said book case section below said top to permit the free end of the black-board to be placed on the lap of the user with one opaque face exposed, and a prop member for supporting said blackboard member with its free end elevated and the other opaque surface exposed when said top has been moved to open position, said prop member being contained within the table or stand beneath said top when the latter is closed.

In testimony whereof I have signed my name to this specification in the presence of two subscribing witnesses.

WILLIS C. MILES.
